UNITED STATES PATENT OFFICE.

JOHN S. BRENNAN, OF MILWAUKEE, WISCONSIN.

FUEL-RESERVOIR.

1,376,859.

Specification of Letters Patent.

Patented May 3, 1921.

Application filed May 18, 1920. Serial No. 382,366.

To all whom it may concern:

Be it known that I, JOHN S. BRENNAN, a citizen of the United States, and resident of Milwaukee, in the county of Milwaukee and State of Wisconsin, have invented certain new and useful Improvements in Fuel-Reservoirs; and I do hereby declare that the following is a full, clear, and exact description thereof.

10 My invention relates to new and useful improvements in reservoirs adapted for use on oil stoves, and of that type shown in my co-pending application for Patent No. 1,343,343, granted June 15, 1920, wherein there is provided a main supply receptacle detachably mounted in inverted position over an auxiliary constant level receptacle, and having means carried by its neck and engaging the auxiliary constant level receptacle 20 whereby to afford a vertical support for the main receptacle so that the desired constant level line of fluid in the auxiliary receptacle is not affected by possible variation in the length of the neck of the main receptacle, 25 which would preferably be made of glass and consequently liable to such variation.

It is the object of my invention to improve the conditions of support afforded the main supply receptacle, whereby to procure 30 a maximum firmness of support in a manner which is most economical of the materials employed. And it is more particularly my object to eliminate adverse leverage conditions in a structure of the present 35 type with respect to lateral stresses which may be imparted to the structure in use.

A further object resides in the provision of means for affecting lateral support of the main receptacle, which may be formed in a 40 most economical manner of bent wire or strips and wherein the stresses incidental to lateral support of the main receptacle are imparted therethrough longitudinally of the general plane of said support means.

45 With the above and other objects and advantages in view, which will be apparent as the description proceeds, my invention resides in the novel features of construction, combination and arrangement of the 50 parts as hereinafter described and defined by the appended claims.

In the accompanying drawings:

Figure 1 is a side elevational view of my improved reservoir structure and support

means therefor, the auxiliary reservoir and 55 main reservoir valve being shown in section.

Fig. 2 is a transverse sectional view on the line 2—2 of the Fig. 1, and

Fig. 3 is an elevational view of the lateral support wire structure, parts associated 60 therewith being conventionally shown.

Fig. 4 is a side elevational view partly in section, of a modified form of my invention.

Fig. 5 is a plan view of this modification. 65

Fig. 6 is an elevational view, partly in section of another modification of my invention.

Fig. 7 is a plan view, partly in section of the modification shown in Fig. 6.

Fig. 8 is a view similar to Figs. 1, 4 and 70 6 of a still further modification of the invention.

Fig. 9 is a part plan and part sectional view of the modification shown in Fig. 8, the main receptacle having been removed. 75

Fig. 10 is a detail elevation of the lateral support used in the modified form of the invention illustrated in Figs. 8 and 9.

Referring to the drawings, especially to Figs. 1 to 7 inclusive, 5 designates the 80 usual pan-shaped auxiliary receptacle of an oil stove, having a supply pipe 6 depending from its bottom at one side, said receptacle being braced by a pair of slightly divergent bars 7 extending from its wall portion to the 85 adjacent wall 8 of the stove. The main receptacle 9, comprising the usual glass bottle is inverted over the auxiliary receptacle and has a valve cap 10 threaded on its neck and carrying a valve structure as described in 90 my said allowed co-pending application.

An inner valve casing section 11 is secured within the cap about an outlet port formed by a central aperture in the bottom portion of the cap, the cap material adjacent said aperture being inclined to form a frusto-conical seat for co-operation with the flared upper end of a tubular valve member 12 passed through the cap aperture, said tubular member being closed at its outer end 100 and resiliently urged outwardly by a spring 13 disposed therein and bearing against the casing portion 11. The outer portion of the tubular valve stem 12 is slidably passed through a bearing plate 14 which is spaced 105 from and connected with the end of the cap by the arms 15. Thus when the main receptacle is inverted over and lowered to en-

gage its neck portion into the auxiliary receptacle 5, the stem of the valve member 12 will engage the bottom of the auxiliary receptacle and will hence become disengaged 5 from its seat on the cap member, thus permitting oil to flow freely from the main receptacle into the auxiliary receptacle, to a constant level line which is determined by the end of the cap 10 threaded on the bottle 10 neck.

To insure that possible variation of the length of the bottle neck will not affect the desired plane of the constant level, I associate the vertical support means for the 15 main receptacle with the cap 10 and thus in the present instance the valve stem finds a seat in its inner or open position and said stem engages the bottom of the auxiliary reservoir and takes up the entire vertical 20 stress, although as shown in my co-pending application other support means carried by the cap may be employed to afford the vertical support, the essential feature being that the vertical support is determined by the end 25 of the bottle neck so that a proper elevation of the fluid level line to coöperate with the burner structures is procured irrespective of possible variation of the length of the bottle neck.

30 In Figs. 1, 2 and 3 a band 16 is inset in or otherwise secured to the intermediate portions of the main receptacle 5 and the ends of bowed plates 17 are secured to diametrically opposite portions of this band to form 35 connecting ears for the bail 17' by which the bottle may be carried. This bail attaching means is utilized in the present instance to afford lateral support for the main receptacle, and thus a pair of wire sections 40 have their intermediate portions looped at 18 and secured by bolts 19 to the stove wall 8. One pair of ends of the wire sections are extended outwardly a slight distance in parallel relation and are then oppositely curved to provide portions 20 partially embracing the main receptacle, the ends of said portions being bent downwardly to provide lug members 21 engageable with the sockets formed by the bowed 45 bail attaching plates 17.

The other end portions of the main wire sections are bent forwardly at 22 below the first named end portions and have their extremities directed upwardly and converged 55 for mutual engagement to form a lug member 23 which is engageable selectively in one of a pair of socket plates 24 secured to the band 16 of the main receptacle at quadrantly spaced points with respect to the bale 60 plates 17. The disposition of the lug members 21 and 23 in the sockets of the main receptacle thus serves to afford the lateral support means for the main receptacle, but it is particularly noted that this structure 65 does not interfere with the vertical move-

ment of the main receptacle to procure this vertical support by seating engagement of its cap carried member on the bottom of the auxiliary receptacle, and if by any chance said wires would tend to obstruct 70 such vertical movement of the main receptacle the wires would yield by their natural resilience inasmuch as the vertical stress would be exerted transversely on the general plane of the wire.

75 Referring now to the modification shown in Figs. 4 and 5, it will be seen that the bail carrying band 16 is not used except for the purpose of manually placing the main receptacle 9 into or removing same from the auxiliary receptacle 5. The vertical support of the main receptacle is procured in the same manner as in the form of the invention depicted in Figs. 1, 2 and 3, but said main receptacle is retained against 80 lateral movement by a somewhat different means. In this form a horizontally disposed retaining band 30 is secured to the stove wall and is designed to receive the main receptacle when the same is inserted. Connection between the band 30 and the stove wall is obtained by means of a pair 85 of metal strips bent into substantially U-shape; these strips having their intermediate portions disposed in engagement to 90 form a shank 31, while their arms 32 and 33 are extended in opposite directions as shown in Fig. 5. The arms 32 provide attaching means for securement to the stove wall; the other arms 33 being connected 95 with the band 30.

A third means of holding the main receptacle 9 against lateral shifting is illustrated in Figs. 6 and 7, and in this instance the usual receptacle carried band 16 is provided 105 with a relatively long hook plate 34 which, when the receptacle is inverted extends downwardly as shown. This hook plate is adapted to seat in a socket 35 carried by the stove wall 8, and in constructing this socket 110 a piece of strap metal is bent to form the socket at one end and a pair of oppositely extending attaching arms 36 at the other, these arms being bolted or riveted to the 115 stove wall as at 37.

In Figs. 8, 9 and 10 another means is shown for providing both vertical and lateral support for the main receptacle 9. However, in the use of this modification, the main receptacle is inverted in an auxiliary receptacle 5' of substantially the same shape as the receptacle 5, the same having a feed pipe 6' leading from its bottom to the burners within the stove S. In this case the auxiliary receptacle 5' has its edge reinforced as at 38 and the main receptacle 9 seated thereon to be thus vertically supported.

120 A bracket plate 39 depends from the top T of the stove, it being secured thereto at one 130

end and having a lateral auxiliary receptacle supporting arm 40 at the other or lower end. This arm braces the auxiliary receptacle in substantially the same manner 5 as the member 7 of the other forms of the invention as shown from the figures preceding Figs. 8, 9 and 10. The bracket plate 39 is formed of a single piece of material and has its edge portions bent laterally to provide 10 strengthening flanges 41. The intermediate portion of the vertical part of the bracket plate 39 has a pair of tongues 42 and 43 struck therefrom, both of which are substantially right angular and have their 15 vertical free ends positioned for engagement with the wall of the main receptacle 9. The tongue 42 constitutes an attaching member and is engaged in one of the sockets 24, which are formed on the receptacle carrying 20 band 16. The other or depending tongue 43 provides a base for engagement with the wall of the main receptacle 9.

By securing the lateral support means of the main receptacle to the stove structure 25 above the auxiliary receptacle, it is seen that the lateral stresses incidental to lateral support of the receptacle are exerted in a direction longitudinally of the general plane and extent of the lateral support means, thus 30 providing a sufficiently durable and strong structure with a maximum lightness and economy of material and the advantages of this lateral structure are particularly in contradistinction to any lateral support means 35 carried by the auxiliary receptacle, wherein adverse leverage conditions would be set up incidental to lateral stress on the receptacle, which would impart excess load conditions to the support means of the auxiliary 40 receptacle. The advantage of providing vertical support by engagement with the bottom of the auxiliary receptacle has been brought out with respect to the desired uniform elevation of the constant level line. 45 Thus by distributing my various support means in the manner described, I have provided an exceedingly efficient, strong and durable construction, which at the same time permits ready manipulation of the main receptacle for the purpose of removing and 50 filling it.

In using one of the main receptacles with either of the several forms of the invention, it is necessary to invert the former and 55 lower it into the auxiliary receptacle, whereupon its valve is opened and the liquid fuel is permitted to flow from the main receptacle into the auxiliary receptacle to a predetermined level. At the same time the 60 auxiliary receptacle provides a vertical support for the main receptacle while any of the different forms of the lateral supporting means prevents the main receptacle from shifting out of a formal vertical line. It 65 will be noted that in each of the several aux-

illary receptacles, a dished portion 25 is provided to assist in centering the main receptacle which is lowered into engagement with the said auxiliary receptacle. This dished portion also serves as a sediment base 70 designed to accumulate the various impurities which occur in the oil employed in stoves of this character.

From the foregoing description it will be seen that many different arrangements may 75 be provided for affording the lateral support, as well as the vertical support. For instance any of the several lateral supports may be employed in connection with the features of my invention illustrated in my co-pending application above referred to. It is to be appreciated that any of the lateral supporting means prevent sidewise movement of the main receptacle or bottle while readily permitting the vertical movement 85 thereof to or from engagement with the auxiliary receptacle.

What is claimed is:

1. In a constant level fuel supply structure, a main support member, an auxiliary receptacle mounted in stationary relation to said main support member, a main receptacle having its neck portion engageable in the auxiliary receptacle, means associated with the neck of the main receptacle and engaging the auxiliary receptacle to provide vertical support for the main receptacle, lateral support members carried by the main support member and extending substantially 90 in a horizontal plane located intermediately 95 of the normal position of the main receptacle, upstanding lug portions on said lateral support members and socket portions carried by the main receptacle for slidably receiving said upstanding lug portions. 100

2. In a constant level fuel supply structure, a main support member, an auxiliary receptacle mounted in stationary relation to said main support member, a main receptacle having its neck portion engageable in the auxiliary receptacle, means associated 110 with the neck of the main receptacle and engaging the auxiliary receptacle to provide vertical support for the main receptacle, wires secured to the main support and extending outwardly therefrom, upstanding lug members carried by said wires and socket members carried by the main receptacle to receive said lugs. 115

3. In a constant level fuel supply structure, a main support member, an auxiliary receptacle mounted in stationary relation to said main support member, a main receptacle having its neck portion engageable in the auxiliary receptacle, means associated 120 with the neck of the main receptacle and engaging the auxiliary receptacle to provide vertical support for the main receptacle, wires secured to the main support and extending outwardly therefrom, upstanding 125

130

lug members carried by said wires and socket members carried by the main receptacle to receive said lugs.

4. In a constant level fuel supply structure, a main support member, an auxiliary receptacle mounted in stationary relation to said main support member, a main receptacle having its neck portion engageable in the auxiliary receptacle, means associated 10 with the neck of the main receptacle and engaging the auxiliary receptacle to provide vertical support for the main receptacle, wires secured to the main support and extending outwardly therefrom, upstanding 15 lug members carried by said wires bowed bail attaching plates carried by the main receptacle, said plates forming socket members for receiving said lug members.

5. In a constant level fuel supply structure, a main support member, an auxiliary receptacle mounted in stationary relation to said main support member, a main receptacle having its neck portion engageable in the auxiliary receptacle, means associated 25 with the neck of the main receptacle and engaging the auxiliary receptacle to provide vertical support for the main receptacle, a pair of members extending outwardly from the main support member and adapted to 30 embrace the main receptacle, lug portions

carried by said members, a lug member carried by the main support member and disposed between said first named members inwardly of their lug portions and socket members carried by the main receptacle to 35 receive said lugs.

6. In a constant level fuel supply structure, a main support member, an auxiliary receptacle mounted in stationary relation to said main support member, a main receptacle having its neck portion engageable in the auxiliary receptacle, means associated with the neck of the main receptacle and engaging the auxiliary receptacle to provide vertical support for the main receptacle, a 40 pair of members extending outwardly from the main support member and adapted to embrace the main receptacle, lug portions carried by said member, a lug member carried by the main support member and disposed between said first named members inwardly of their lug portions and quadratically spaced sockets carried by the main support member for receiving said lugs.

In testimony that I claim the foregoing 55 I have hereunto set my hand at Milwaukee, in the county of Milwaukee and State of Wisconsin.

JOHN S. BRENNAN.
